UNITED STATES PATENT OFFICE.

EDGAR BOREL, OF NEUCHÂTEL, SWITZERLAND.

DESIGN FOR A PAIR OF SHEARS OR SCISSORS.

48,883.

Specification for Design.

Patented Apr. 18, 1916.

Application filed January 3, 1916. Serial No. 70,050. Term of patent 14 years.

To all whom it may concern:

Be it known that I, EDGAR BOREL, goldsmith, a citizen of the Swiss Republic, residing at Neuchâtel, Switzerland, have invented a new, original, and ornamental Design for Shears or Scissors, of which the following is a specification, reference being had to the accompanying drawing, forming part thereof.

The figure is a front elevation of a pair of shears or scissors embodying my new design.

I claim:—

The ornamental design for a pair of

shears or scissors, the two blades of which each represents a rifle with a bayonet, thus forming the cutting part of the tool; the shoulder belts of the rifles being arranged so as to form the finger loops, as shown.

In testimony whereof I affix my signature in presence of two witnesses.

EDGAR BOREL.

Witnesses:

L. GILLIARD,
T. GILLIARD.
